R. Singer
ATTORNEY

UNITED STATES PATENT OFFICE.

YUJI MUKOJIMA, OF MINOWA, NEAR TOKYO, JAPAN.

DOUBLE-FLOW FOUNTAIN-PEN OR RESERVOIR-PEN.

1,383,416.

Specification of Letters Patent.

Patented July 5, 1921.

Application filed August 3, 1920. Serial No. 400,988.

To all whom it may concern:

Be it known that I, YUJI MUKOJIMA, a subject of the Emperor of Japan, residing at No. 375 Minowa, near the city of Tokyo,

5 Japan, have invented certain new and useful Improvements in Double-Flow Fountain-Pens or Reservoir-Pens, of which the following is a specification.

This invention relates to a new or improved fountain pen or reservoir pen and has for its object to provide a fountain pen in which two kinds of ink of different color may separately be stored and used alternately at will, thus adding greatly to the usefulness of the pen. The pen according to this invention comprises two tubes, an inner and an outer one, forming two chambers for storing ink of different color respectively; and a rear and a front head, 20 each having two conduits adapted to convey the respective ink from the said reservoirs to the nib. One of the heads is fitted to the other in such a way that by rotating the same, the respective supply of ink may 25 alternately be allowed to flow out to the nib, or both flows of ink are cut off, according to the rotary position of one head relative to the other.

In the accompanying drawings in which one embodiment of the invention is shown by way of example, Figure 1 is a side view of the fountain pen constructed according to the invention. Fig. 2 is a longitudinal sectional view of the same. Fig. 3 is a cross section taken on line 3-3 in Fig. 2. Fig. 4 is a cross section taken on line 4-4 in Fig. 2. Fig. 5 is an end view of the reservoir end or head with its front head 2 removed showing the forward end of the rear head 1. Fig. 6 is an end view showing the rear part of the front head 2. Figs. 7, 8 and 9 are sectional views of the rear head 1, the front head 2 and the nib 11, respectively.

45 Referring to the drawings, 1 is a rear head to which is fitted, in a manner hereinafter described, a front head 2 carrying the nib. The head 1 is provided at the rear end with the externally threaded part which 50 is engaged by the internally threaded part of an outer tube or reservoir 3. This outer tube 3 surrounds an inner tube or reservoir 4 but is spaced apart therefrom so as to form an annular ink chamber, as shown in 55 Figs. 2 and 3. The inner tube or reservoir 4 is secured to the threaded flange part

formed at the rear end of the head 1, as shown in Fig. 2. The outer and inner tubes 3 and 4 are provided with suitable covers 5 and 6 respectively. 60

In the rear head 1 a conduit 7 conveys the ink from the outer reservoir to the nib. There is also in the head 1 another conduit 8 starting from the central port 9 at the rear end and extending toward the other 65 end. This conduit 8 is inclined relative to the axis of the head, as shown in Figs. 2 and 7, and conveys a supply of ink from the inner reservoir 4 to the nib.

The front head 2 is fastened to the forward end of the rear head 1 by means of a screw 10 and has a central bore 12 for receiving the nib 11. Said screw 10 passes through a hole 13 which is continuous to the said bore 12 but smaller than the same, and 75 engages a threaded hole 16 in the front of the rear head 1 as shown in Figs. 5 and 7. In Fig. 5 a slot 14 is also shown as formed in the front part of the head 1, this slot being adapted to receive a projection 15 (Fig. 80 6) anchored to the rear end of the head 2. Thus it will be seen that the rotation of the front head 2 relative to the rear head 1 is limited by the slot 14 and the projection 15. Ink conduits 17 and 18 are shown in the 85 front head 2 located opposite one to the other, one leading to the inner side of the nib 11 and the other to the outer side thereof.

In Fig. 1 a suitable mark 19 is shown as provided in the periphery of the front head 90 2, and other suitable marks 20, 21 and 22 are similarly provided in the periphery of the rear head 1. Said mark 19 cooperates with the other marks 20, 21 and 22 and serves to indicate the correct rotary position of the 95 front head 2 relative to the rear head 1.

In this new fountain pen constructed and arranged according to this invention, it will readily be seen that, when the front head 2 is slightly rotated in one direction relative 100 to the rear head 1 bringing the mark 19 toward the mark 22 the conduit 17 will be brought into alignment with the conduit 7 in the rear head 1, thereby communicating with the interior of the outer reservoir 3. 105 Thus the ink of this outer reservoir will be supplied to the nib. When the front head 2 is rotated in the opposite direction bringing the mark 19 toward the mark 20, the ink conduits 18 and 8 will be in alignment, allowing a supply of the ink in the inner reservoir 4 110 to flow out toward the nib 11. When the

mark 19 is brought toward the mark 21, the ink conduits 7 and 8 are now closed by the rear wall of the front head 2, thereby cutting off the flow of both inks, thus the pen 5 is maintained in its inoperative state.

It is to be noted that in the outer and inner reservoirs the inks of different color 10 may respectively be stored, and that one can alternately use at will either of the inks 15 within the reservoirs in the manner described.

I claim:

A fountain pen comprising an inner reservoir tube, an outer tube, and a head at the 15 front ends of said tubes and comprising front and rear members pivotally connected together, said front member having a nib

receiving opening and also having conduits leading from the nib to the rear member, and said rear member having conduits respectively 20 communicating with the interiors of said reservoir tubes, the conduits of said members being so arranged as to enable said front member, by a partial turning movement thereof, to cause ink to alternately flow 25 from either of the reservoirs to the nib, or to be cut off therefrom.

In testimony whereof I affix my signature in the presence of two witnesses.

YUJI MUKOJIMA
